UNITED STATES PATENT OFFICE.

MICHAEL WITT, OF COLUMBUS, OHIO.

PHOTOGRAPHIC-PRINTING FRAME.

Specification forming part of Letters Patent No. 39,191, dated July 7, 1863.

To all whom it may concern:

Be it known that I, MICHAEL WITT, of the city of Columbus, Ohio, have invented a new and Improved Frame or Apparatus for Photographic Printing; and I do hereby declare that the following is a full and exact description thereof, reference being had to the accompanying drawings, and to the letters of reference marked thereon.

The nature of my invention consists in providing a "rabbeted" frame, in which the "negative" is placed and where it is steadily and securely held by a hinged back, having a spring pad or cushion, self-adjusting to any thickness of glass, and composed of two flaps arranged that one may be opened to inspect the progress of the printing, while the other, remaining closed, prevents the sliding or other improper movement of the paper.

The following description will enable persons of ordinary skill to make and use my invention: A is a frame, of any suitable size, with a rabbet formed on the inside to hold the negative B. The back of the apparatus consists of two flaps, C D, attached by hinges and secured when closed by the latches E.

The flaps are provided with cushions of sheet-brass or other suitable material, F, which cushions are secured to the flaps in such a manner as to be acted upon by the spring G, Fig. 2, so as to adjust the cushion to different thicknesses of glass in the negatives.

The apparatus is used by placing the negative in the frame, laying the prepared paper thereon, covering the paper with the black velvet apron x, closing the backs, and exposing the frame to the sun.

The manner of examining the progress of the work and the use of the two flaps or backs is shown in Fig. 3.

What I claim as my invention, and desire to secure by Letters Patent, is—

The application of the self-adjusting spring-cushions to the two flaps or back of the frame, arranged and operated for the purposes set forth and shown, or any other arrangement, substantially the same for the accomplishment of the same end.

M. WITT.
